UNITED STATES PATENT OFFICE.

BENJAMIN FRANKLIN PARTRIDGE, OF PORTSMOUTH, MICHIGAN.

CARRIAGE-COVER.

SPECIFICATION forming part of Letters Patent No. 447,842, dated March 10, 1891.

Application filed August 20, 1890. Serial No. 362,481. (No model.)

To all whom it may concern:

Be it known that I, BENJAMIN FRANKLIN PARTRIDGE, residing at Portsmouth, in the county of Bay and State of Michigan, have invented certain new and useful Improvements in Carriage-Covers; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to carriage-covers; and its objects are, first, to raise and lower the same with facility; second, to prevent undue wear at the corners of the covers; third, to adapt the area of the cover readily to the area of the carriage; fourth, to attain the facile adjustment of the co-operating parts, and, fifth, to accomplish these ends with structural simplicity and economy. I secure these purposes by the device shown in the accompanying drawings, in which—

Figure 1 represents a sectional elevation of a stable having my cover adjusted therein. Fig. 2 is a plan view of the top frame. Fig. 3 is a detail view of the joint employed to facilitate the adaptation of the size of the cover to that of the carriage it is desired to envelop. Fig. 4 is a detail of the cover-piece employed on the bottom frame. Fig. 5 is a plan view of the top frame, partly in section; and Fig. 6 shows the application of the lower frames to the corners of the curtain.

The same designations indicate corresponding parts in the several views.

Heretofore the use of carriage-covers has resulted in undue wear at the corners and at the folds. This was owing to a defective construction of the frame whereon the cover hangs. To the end of overcoming these defects my invention is addressed.

A represents a carriage-house, to the ceiling whereof hooks F' are secured, wherefrom the cover B is suspended by cords C, whose

knotted ends are passed through perforations in the cover. Pulleys F are also attached to the ceiling, through which the ends of the cord D pass to the bottom of the cover, (after 50 passing a series of eyes I,) being held therein by terminal knots. A central hook F², likewise secured in the ceiling, serves to permit the vertical reciprocation of the cord D, which insures a synchronous raising and lowering of 55 the cover to permit the withdrawal or insertion of a carriage. The cover is held between the upper frame (represented in Fig. 2) and the counterpart corner-pieces. (Shown in Fig. 4.) The upper frame is made by crossing pivotally two equal rods H, secured at O and having metallic ends G', secured adjustably by pins R P, which are passed through slots in the metallic corners S and have terminal perforations G through which to pass the cord D. 60 The corners S are secured telescopically at one arm to the end piece M and at the other arm to the jointed sides L, having central joints l, pivoted at K', to facilitate altering the size of the frame. The series of frame- 65 rods J, whereto the lower corners of the curtain are secured, are held by corner-pieces J', provided with perforations K, wherein the ends of the cord D are knotted.

Having thus fully described my improvements, what I claim is—

The carriage-cover B, having eyes I at the folds, in combination with the frames between which it is suspended, the upper of which is provided with rounded slotted corners, adjustable jointed rods L, and the variable cross-frame H, the rope D, fastened to the base of the cover at opposite ends and passing through eyes I', the pulleys F, the hooks F², and the eye F³, the whole co-operating, as and for the 85 purpose set forth.

In testimony whereof I affix my signature in presence of two witnesses.

BENJAMIN FRANKLIN PARTRIDGE.
